CLAIM

The ornamental design for a motion detector, as shown and described.

DESCRIPTION

1. Motion detector

1.1 is a front perspective view of a motion detector showing our new design;

1.2 is a front elevation view thereof;

1.3 is a rear elevation view thereof;

1.4 is a left side elevation view thereof;

1.5 is a right side elevation view thereof;

1.6 is a top plan view thereof;

1.7 is a bottom plan view thereof;

1.8 is a front perspective view of an exemplary electronic device with the motion detector installed; and

1.9 is an exploded front perspective view of the exemplary electronic device shown in 1.8.

The broken lines in the reproductions illustrate portions of the motion detector and an exemplary electronic device that form no part of the claimed design.
